Primary Examiner — April Rivas(74) *Attorney, Agent, or Firm* — K&L Gates LLP(57) **CLAIM**

The ornamental design for a motorized suitcase pull handle, as shown and described.

DESCRIPTION

FIG. 1 is a perspective view of a motorized suitcase pull handle with retracted pegs upon a motorized suitcase showing our new design;

FIG. 2 is an inverted perspective view thereof;

FIG. 3 is a left-side view thereof;

FIG. 4 is a right-side view thereof;

FIG. 5 is a back view thereof;

FIG. 6 is a front view thereof;

FIG. 7 is a top view thereof;

FIG. 8 is a bottom view thereof; and,

FIG. 9 is a perspective view of a motorized suitcase pull handle with extended pegs upon a motorized suitcase.

Those portions of the figures that are presented in broken lines merely illustrate the environment of the design and are not part of the claimed design.

1 Claim, 9 Drawing Sheets(56)
